UNITED STATES PATENT OFFICE.

JAMES A. JOHNSON, OF DANVILLE, VIRGINIA, ASSIGNOR TO VIRGINIA TOBACCO CURE COMPANY, INCORPORATED, A CORPORATION OF VIRGINIA.

OIL BURNER FOR TOBACCO BARNs.

Application filed December 8, 1923. Serial No. 679,449.

To all whom it may concern:

Be it known that I, JAMES A. JOHNSON, a citizen of the United States, residing at Danville, in the county of Pittsylvania and State of Virginia, have invented certain new and useful Improvements in Oil Burners for Tobacco Barns, of which the following is a specification, reference being had to the accompanying drawings.

10 This invention relates to heating apparatus, and particularly to an oil burner for use in heating tobacco-curing barns.

Tobacco barns are ordinarily heated with wood or coal stoves or furnaces, and inasmuch as wood is getting scarce and coal is relatively hard to get and high-priced, it is becoming accordingly more costly and difficult to properly cure the tobacco. Furthermore, wood and coal burning stoves or furnaces so used are very liable to produce sparks which set barns on fire.

In order to eliminate these difficulties, I have devised an oil burner which is particularly adapted for use within a tobacco barn, and the object of my invention is to provide an oil burner for use with this apparatus which is so constructed that the flame or jet directed from the nozzle of the burner may be discharged against a series of baffle members upon which the flame plays, these baffle members being so formed that they will prevent the immediate dissipation of the heat and the passage of the heat rapidly through the flues of the apparatus and will act to heat and secure an even distribution thereof such as is necessary in curing tobacco.

Another object is to provide a device of this character in which the baffles may be readily adjusted and more or less of the baffles put in place or the baffles separated from each other a greater or less distance to thus regulate the amount of heat within the barn.

Still another object is to provide an apparatus of this character in which the heat from the burner is directed into flues which extend around through the barn, these flues carrying at intervals apertured, relatively thick, metallic disks which act to retard the passage of the heat and which, by absorbing heat, tend to render the heat uniform throughout the entire barn and prevent its too rapid dissipation.

Other objects will appear in the course 55 of the following description.

My invention is illustrated in the accompanying drawings, wherein:—

Figure 1 is a top plan view of a tobacco barn, the walls being in section, showing my 60 improvement applied thereto;

Figure 2 is a longitudinal sectional view through the heater and vaporizer;

Figure 3 is a fragmentary top plan view of the vaporizer and the conical members 65 mounted thereon;

Figure 4 is a fragmentary longitudinal horizontal section through the vaporizer, showing the bottom thereof;

Figure 5 is a horizontal sectional view 70 through the burner;

Figure 6 is a vertical section therethrough on the line 6—6 of Figure 5;

Figure 7 is an end view of one of the baffles 75 26;

Figure 8 is an edge view of one of the baffles 26;

Figure 9 is an elevation of the fuel tank and compressed air tank;

In Figure 1, I have illustrated diagrammatically a tobacco barn A which, of course, may be of any suitable construction or character.

Disposed within this barn at any suitable location, preferably adjacent one wall of the barn, is a casing 10 which may be 80 made of sheet metal or might be made of brick, tile or other suitable non-combustible material, this casing 10 having therein the burner, as will be later described, and having extending therefrom a flue 11. This 85 flue 11 is illustrated as intersecting and opening into a cross flue 12 having arms 13 which extend parallel to the flue 11 and on each side of the heater and extend to the exterior of the barn, where they are connected to stacks 14. This is purely a diagrammatic illustration of the flues and it will be understood that the flues might extend in any desired direction through the barn and that there may be as many 90 branches from the flue 11 as desired. Of course, the number of branches, the length of the flues, etc., will depend upon the size of the barn and the amount of tobacco which is to be cured therein.

Within the casing 10 is disposed a burner comprising a relatively long and relatively narrow hollow member 15 which is illus-

trated as approximately rectangular in cross section and has, generally speaking, the form of a covered trough, one end of this hollow member being upwardly and forwardly curved, as at 16. The bottom of this hollow member is formed with transverse corrugations 17 which may be of any suitable character, these corrugations merely acting to retard the flow of oil along the 5 bottom of this trough-shaped member and spread the oil in a thin film over the trough. I do not wish to be limited to the character of these corrugations 17. They may extend entirely across the bottom of the trough or 10 the corrugations may be disposed in staggered relation.

Entering the upper end of the portion 16 is a supply pipe 18 which extends from any suitable tank 19 which is so disposed as 20 to cause the oil to flow through the pipe 18 and to be discharged into the upper end of the vaporizing trough 15. The oil trickles down past the corrugations and in doing so is vaporized and gasified. From the opposite end of the trough 15 extends a burner supply pipe 20. To the upper end of this pipe is connected a nozzle 21. This nozzle is oscillatably mounted upon the upper end of the supply pipe and is provided with a 25 handle 22 upon the exterior of the casing whereby the nozzle may be directed upward or downward and held in any adjusted position by a bolt 20° passing through the upper end of the supply pipe 20 and the nozzle, the nozzle being rotatably mounted upon the side of the supply pipe.

Preferably the top of the vaporizing chamber or trough 15 has lateral flanges 23, and disposed between these flanges are 30 the bases of a plurality of baffle members 24. The base of each baffle member has a length equal to the distance between the flanges 23, and extending upward from each base is a plurality of conical bosses 25. 35 These are relatively high. The nozzle 21 is so formed as to direct the ignited jet issuing therefrom against the baffles, and preferably the nozzle is disposed somewhat above the level of the apices of the conical 40 baffles so that the jet may be discharged downward and forward and in a manner to strike all of the baffles or only some of the baffles. These baffles become very highly heated and act to transmit heat to the vaporizing trough 15, to diffuse the heat of the flame, and to secure more perfect combustion than otherwise would be secured. 45 These baffles are adapted to be shifted along the upper face of the trough in accordance with conditions with the tobacco barn, and I have found that by shifting these baffles along the upper wall of the vaporizing trough that any required regulation of heat 50 may be secured. Obviously also more or less baffles may be used. These baffles may

be shifted along the trough by simply inserting a hook-shaped adjusting rod through the rearward end of the casing and shifting the baffles backward or forward along the upper wall of the vaporizing chamber. 70 The lever 22 permits the nozzle to be directed either toward the apices of the several baffles or against the bases thereof and thus also the heat may be regulated.

This heat is further controlled and prevented from too rapid dissipation and passage up the stacks by means of a series of iron disks 26. These disks 26 are relatively thick and are apertured for the passage of the heat and products of combustion, and while the apertures permit the passage of the heat through the various flues to the stacks 14, the too rapid passage of the heat is impeded, and furthermore these disks retain the heat and hold it so that once the disks are heated, then even after the burner has been turned off entirely a certain degree of heat will be held within the bar. I regard this heat dissipation impeding means as of great value in the curing of tobacco. 90

Preferably the fuel is fed to the burner by means of compressed air, and I have indicated for this purpose an air tank 27 which may be filled with compressed air, as by means of a pump, and which is connected to the oil tank 19 above the surface of the oil by means of a hose connection 28, there being suitable valves controlling the supply of air to the tank and suitable valves for controlling the supply of oil to the burner. Of course, the outlet of gas from the nozzle 21 will be controlled by means of a needle valve 29 of any suitable or usual construction. Of course, it will be obvious that the tank holding oil might be disposed at a higher level than the burner, in which case the oil would feed by gravity to the burner, but where the oil tank is disposed on the same level as the burner it is necessary that there should be a low pressure 105 upon the surface of the oil in order to cause it to feed.

In the use of this apparatus, the flame issuing from the jet nozzle 21 may be directed downward immediately against the top of the vaporizing chamber 15 and this will vaporize the oil therein. Then as the chamber grows hotter the flame may be directed against the baffles 24 and taken off the top of the vaporizing chamber. These baffles will communicate enough heat, however, to the vaporizing chamber to cause the vaporization of the oil therein. The flame may be directed against all of the baffles or against the nearest baffle or otherwise shifted and the baffles shifted so as to secure a perfect regulation of the heat given out. The baffles cause the heat to be retained to a certain degree within the casing 10 and this heat is carried from the end of the casing by the flue 110 115 120 125 130

11 to the flues 12 and 13. The disks 26, which constitute radiators and also check the too quick flow of the heated air, are disposed about two feet apart. Without these radiators at least one-half the heat would pass out of the barn very rapidly. Where coal or wood burners have been used for the purpose of heating the barn, it has been necessary to have a good draft, but with a system of the character which I have described a draft is not necessary. Only sufficient air is admitted to the burner to secure the full combustion of the oil and thus the heat can be held in the barn to any desired extent. In curing 15 tobacco from 90° to 100° F. is required for the first twenty-four hours. In finishing the curing it is necessary that the heat should be run up from 200° to 225° F. This heat may be regulated by controlling the disposition of the baffles 24 and also by controlling the discharge of jet from the nozzle 21 by means of the needle valve 29. Obviously if it is not desired to cause the flame to play upon a large number of baffles 24 these may 20 be shifted away from the flame and the flame allowed to play only on a relatively small number.

A trough 30 is disposed upon the floor of the heating chamber 10, the trough carrying 25 a wick which is adapted to be soaked in kerosene in order that initial heat may be applied to the burner. Preferably the rear end 10^a of the casing is entirely removable so as to permit the removal or replacement of the generating apparatus, this rear well 10^a being provided with means whereby access may be had to the valve handle 22 and means whereby air may be supplied to the interior of the chamber 10, this means being illustrated as a pivoted door 31 and a rotatable 30 damper 32. Obviously I do not wish to be limited to these details.

I claim:—

1. In an apparatus of the character described, a vaporizing burner comprising a longitudinally extended chamber having a top, the chamber being so formed as to cause liquid fuel to flow from one end of the chamber toward the other, a burner pipe leading 45 from the end of the chamber toward which the liquid fuel flows and receiving vapor from the chamber, a nozzle mounted upon the burner pipe and directed longitudinally of the chamber, and a series of baffle members supported upon the upper wall of the chamber in the path of movement of the flame issuing from the burner pipe.

2. In an apparatus of the character described, a vaporizing burner comprising a longitudinally extended chamber having a top, the chamber being so formed as to cause liquid fuel to flow from one end of the chamber toward the other, a burner pipe leading 50 from the end of the chamber toward which

the liquid fuel flows and receiving vapor from the chamber, a nozzle mounted upon the burner pipe and directed longitudinally of the chamber, and a series of baffle members supported upon the upper wall of the chamber in the path of movement of the 65 flame issuing from the burner pipe, said baffles being shiftable longitudinally along the chamber toward and away from the burner pipe and the nozzle being adjustable to control the angle of the flame as it strikes 70 said baffles.

3. In an apparatus of the character described, a vaporizing burner comprising an elongated chamber having a top, one end of the chamber being higher than the other end, means within the chamber for impeding the flow of oil toward the lower end of the chamber, means for feeding oil into the upper end of the chamber, a burner pipe leading from the other end of the chamber and receiving vapor therefrom, and a nozzle mounted upon said burner pipe and discharging the flame downward against the 75 top of the vaporizing chamber.

4. In an apparatus of the character described, a vaporizing burner comprising an elongated chamber having a top, one end of the chamber being higher than the other end, means within the chamber for impeding the flow of oil toward the lower end of the 80 chamber, means for feeding oil into the upper end of the chamber, a burner pipe leading from the other end of the chamber and receiving vapor therefrom, a nozzle mounted upon said burner pipe for oscillation in a vertical plane and having a controlling valve, means for oscillatably adjusting the nozzle to discharge the flame downward against the top of the vaporizing chamber and control the angle of the flame, and a 85 series of baffle members supported upon the upper wall of the vaporizing chamber and shiftable independently of each other along the top of the vaporizing chamber toward or from the nozzle and against which the 90 flame from the nozzle may be directed.

5. In an apparatus of the character described, a vaporizing burner comprising a trough-shaped chamber having a top, one end of the chamber being upwardly turned, the bottom of the chamber being formed with oil-diffusing corrugations, a pipe leading from a source of supply into the upper end of said chamber and discharging oil thereinto, a burner pipe leading from the other end of the chamber and receiving vapor therefrom, a nozzle mounted upon said burner pipe for oscillation in a vertical plane and having a controlling valve means whereby the nozzle may be oscillated to discharge the flame downward against the top of the vaporizing chamber or discharge the flame in an approximately hori- 100 105 110 115 120 125

zontal plane, and a series of baffle members supported upon the upper wall of the vaporizing chamber and shiftable independently therealong and against which the flame may 5 be directed.

6. In an apparatus of the character described, a vaporizing burner comprising a trough-shaped chamber having a top, one end of the chamber being upwardly turned, 10 the bottom of the chamber being formed with oil-diffusing corrugations, a pipe leading from a source of supply into the upper end of said chamber and discharging oil thereinto, a burner pipe leading from the 15 other end of the chamber and receiving vapor therefrom, a nozzle mounted upon said burner pipe for oscillation in a vertical plane and having a controlling valve, means whereby the nozzle may be oscillated 20 to discharge the flame downward against the top of the vaporizing chamber or discharge the flame in an approximately horizontal plane, a series of baffle members supported upon the upper wall of the vaporizing chamber, 25 and shiftable independently therealong and against which the flame may be directed, said baffles each comprising a base extending transversely of the vaporizing chamber,

and a series of conical projections formed upon each base.

7. In an apparatus of the character described, a casing, a longitudinally extending, hollow, vaporizing chamber disposed in the casing and including a bottom wall and a top wall, the interior surface of the bottom wall being transversely corrugated and one end of the vaporizing chamber being turned upward, a supply pipe discharging into the upper end of the vaporizing chamber, a burner pipe extending upward from the other end of the vaporizing chamber and taking vapor therefrom, a nozzle mounted upon said last named pipe for oscillation in a vertical plane, a handle mounted upon the exterior of the chamber whereby the nozzle may be oscillatably adjusted, and a series of baffle plates mounted upon the upper wall of the chamber and shiftable independently therealong and against which the flame may be caused to play, each baffle plate comprising a base, and a plurality of upwardly 40 extending bosses on the base.

45 In testimony whereof I hereunto affix my signature.

JAMES A. JOHNSON.
